UNITED STATES PATENT OFFICE.

LEON T. J. LUBIN, OF BOSTON, MASSACHUSETTS.

SHOULDER-BRACE.

SPECIFICATION forming part of Letters Patent No. 380,265, dated March 27, 1888.

Application filed December 22, 1887. Serial No. 258,714. (No model.)

To all whom it may concern:

Be it known that I, LEON T. J. LUBIN, of Boston, in the county of Suffolk and State of Massachusetts, have invented certain new and 5 useful Improvements in Shoulder-Braces, of which the following is a full, clear, and exact description.

This invention relates to improvements in shoulder-braces; and it consists, substantially, 10 of two plates or shoulder-blade pieces, preferably triangular in shape, arranged side by side and connected together at one of their edges by an elastic or non-elastic or other suitable material, or a lacing-cord, either elastic 15 or non-elastic, and each having a shoulder strap or loop, of webbing or other suitable material, secured to it, and to which shoulder strap or loop is secured a depending strap, of webbing or other suitable material, and each 20 of said plates or shoulder-blade pieces having attached thereto a depending strap, of webbing, &c., to the free ends of which depending straps can be secured in any suitable manner any 25 article of clothing of the person, all substantially as hereinafter fully described, reference being had to the accompanying sheet of drawings, in which—

Figure 1 represents, in back view, a shoulder-brace constructed in accordance with this 30 invention; and Fig. 2 a detail section, in modification.

In the drawings, A and B represent two triangular plates or pieces, preferably made of cloth and in any suitable manner, as at C, and 35 each having at and along its edge *a* a strip or piece of leather, D, one on each side of the cloth piece C, and all secured together by stitches *b*, and having at or near or along its edge a series of eyelet-holes, E, through which 40 runs a lacing-cord, F, and properly secured and preferably elastic, by which the two parts A B are secured together, as shown, and by which they can be easily and conveniently adjusted, as to their nearness to or distance from 45 each other, by tightening or loosening the cord for the better fit of the shoulder-brace to the person and to increase or decrease the backward pull upon the person's shoulders.

The parts A B are preferably made of the 50 shape shown, and each to conform to or substantially to the shape of the scapula or shoul-

der-blade, over which it is placed when worn, and to better fit the same they are made slightly bulging outwardly or hollowing or concave on their sides that come next to the 55 body when worn. Each one, however, can be cut out in its middle portion, or each can be made of strips secured together to leave an open space in the middle for the same purpose.

Each shoulder-blade piece A B has a loop 60 or shoulder-strap, G, secured by its two ends, *d*, to its shoulder-blade piece by stitches at *f* and each of these shoulder straps or loops G has a depending strap, H, secured to it by 65 stitches, and each shoulder-blade piece also has a depending strap, J. The shoulder-loop straps and the several depending straps H J are preferably made of the usual webbing, and preferably elastic, and they can be secured to their respective supports in any suitable manner, or the straps H can be secured 70 to their respective shoulder-loop straps by loops *g*, as shown in cross-section in detail, Fig. 2, so that each can slide or move along the shoulder-loop strap for its better adjustment under the armpit and its connection to the clothing to be secured thereto, or it can be connected by buckle or in any suitable manner. When in use, each arm of the person is placed through its respective loop G, 80 so that each plate or shoulder-blade piece A B will come against its respective shoulder-blade of the person.

If desired, when worn by a gentleman, the straps H can be connected to a buckle on the 85 usual straps or suspender-ends at the front of the pants, and the straps J by buckles to the usual straps or suspender-ends at the back of the pants, or in any suitable manner; but when worn by ladies the straps H J can be connected to buckles secured to a waist-belt, &c., or by loops to slide back and forth thereon, to which belt the clothing can be secured in any suitable manner, or the straps can be secured directly to the skirt-bands in any suitable manner.

The two shoulder-blade pieces A B can be secured together by elastic straps, one at the top and the other at the bottom, secured thereto in any suitable manner, in lieu of by lacing-cords, and the shoulder straps or loops G and other straps H J can be secured in other

ways than as shown; also, if desired, the several depending straps can be lengthened and be adapted in the usual ways to be secured directly to the article of clothing, in lieu of 5 by independent straps or belts.

The two shoulder-blade pieces can be made of other shapes than triangular, as shown; also, they can be made of any suitable material and in any suitable manner.

10 The strap J can be secured to its shoulder-blade piece at any point desired.

Having thus described my invention, what I claim is—

15 1. A shoulder-brace consisting of two parts or shoulder-blade pieces, A B, connected by a yielding or elastic fastening, and each having a depending strap, J, and a loop or shoulder-

strap, G, which loop or shoulder-strap has a depending strap, H, substantially as and for the purpose specified.

2. A shoulder-brace consisting of two parts or shoulder-blade pieces, A B, connected together by a lacing-cord, F, elastic or non-elastic, and each having a depending strap, J, and a loop or shoulder-strap, G, which loop 25 or shoulder-strap has a depending strap, H, substantially as and for the purpose specified.

In testimony whereof I have hereunto set my hand in the presence of two subscribing witnesses.

LEON T. J. LUBIN.
